UNITED STATES PATENT OFFICE.

AARON RATNER, OF NEW YORK, N. Y.

CLOTH-PILE.

No. 923,578.

Specification of Letters Patent.

Patented June 1, 1909.

Application filed October 12, 1908. Serial No. 457,257.

To all whom it may concern:

Be it known that I, AARON RATNER, a citizen of the United States, residing at New York, in the county of New York and State 5 of New York, have invented certain new and useful Improvements in Cloth-Pilers; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 The present invention relates, generally, to improvements in machines for stretching and forming layers of fabric upon cutting tables, such as are used by manufacturers of underwear and the like; and, the invention has 20 reference, more particularly, to a novel machine or apparatus comprising mechanism by means of which the bolts or rolls of fabric which are carried on a truck or carrier adapted to travel back and forth, from one end of 25 the cutting table to the other, are automatically spread in layers, one above the other, upon the said cutting table, and the material or fabric is also automatically clamped at each end, thus saving time and manual 30 labor consumed in laying out and stretching the fabric upon the usually long cutting tables by hand, as is ordinarily the practice preparatory to cutting garments, underwear, and many other similar articles.

35 The present invention therefore, has for its principal objects to provide a novel, simple and cheaply constructed apparatus of the general character hereinafter set forth, in which the various parts of the mechanism, 40 while automatic and effective in their operations, have been greatly simplified and reduced to a minimum; and, by means of which the layers of fabric may be quickly, evenly and smoothly stretched and clamped 45 one above the other, ready for cutting.

A further object of the present invention is to provide, in connection with the truck or carrier upon which the bolts or rolls of fabric are carried, a pair of spreader-blades, and 50 means connected with said spreader-blades for automatically adjusting the same vertically, so that, while the pile of fabric-layers increases in height, the said spreader-blades are automatically adjusted, in order that 55 they are maintained in their spreading or op-

erative position, always raised slightly above the top-layer of fabric, and that the said spreader-blades do not drag upon the said fabric, thereby reducing the friction, and rendering the operation of the truck or carrier 60 much easier.

A further object of the present invention is to provide a clamping means at each end of the cutting table which will firmly and securely retain the ends of the layers of fabric deposited thereon, and thus keep the said layers of fabric smooth and unwrinkled or creased; and, furthermore, to provide a clamp which is automatically operated by contact with the traveling truck or carrier. 70

Other objects of this invention not at this time more particularly mentioned will be clearly understood from the following detailed description of the same.

With these various objects of the present 75 invention in view, the said invention consists, primarily in the novel machine for stretching or forming layers of fabric upon a cutting table, hereinafter more fully set forth; and, furthermore, this invention consists, in the novel arrangements and combinations of devices and parts, as well as in the details of the construction of the same, all of which will be hereinafter more fully described, and then finally embodied in the 80 clauses of the claims which are appended to and which form an essential part of this specification.

The invention is clearly illustrated in the accompanying drawings, in which:— 90

Figure 1 is a side elevation of a cutting-table equipped with the novel machine or apparatus for stretching or forming thereon the layers of fabric to be cut, the said machine embodying the principles of the present invention. Fig. 2 is a top or plan view of the same, one end of the cutting table being represented as being broken away and the clamp thereon being omitted from said view. Fig. 3 is a longitudinal 100 vertical section of the truck or carrier, said section being taken upon line 3—3 in said Fig. 2, and being made on an enlarged scale, showing the said truck as it is approaching a clamping device and about to automatically 105 operate the same to deposit one end of a fabric layer thereunder. Fig. 4 is a similar view, illustrating the said truck or carrier still further advanced toward the clamping device and lifting the same, while a spreader- 110

blade of said truck or carrier deposits the end of the layer of fabric under the holding or retaining weight of the clamping device. Fig. 5 is a view of the said truck or carrier and clamping device in the same position as shown in said Fig. 4, except that the section is taken centrally through both the truck or carrier and the clamping device. Fig. 6 is a detail longitudinal vertical section of the 10 said clamping device, taken on line 6—6 in said Fig. 2, but showing the holding or retaining weight of the clamping device in its raised position.

Similar characters of reference are employed in all of the above described views, to indicate corresponding parts.

Referring now to the several figures of the drawings, the reference-character 1 indicates a cutting table or bench of any usual construction. Mounted upon said cutting table or bench, and adapted to travel back and forth thereon, is a suitable truck or carrier, comprising a frame-work 2 which is provided with suitably disposed flanged wheels 3 adapted to engage with the longitudinal sides or marginal edges of the said cutting table 1. Secured in any suitable manner to the frame-work 2 of the truck or carrier is a platform 4 upon which may be placed, and 20 are carried thereon, the bolts or rolls of cloth or other fabric, as 5, to be spread or stretched upon the said cutting table or bench in the manner to be hereinafter more fully set forth. Secured to the said frame-work 2 of the truck 25 or carrier are suitably formed arms or brackets 6, preferably one upon each side of the truck or carrier, and mounted in the free end-portions 7 of said arms or brackets, so as to extend laterally across the said truck or carrier, and above the said platform 4 thereof, is a guide-rod 8, over which the said fabric 5 is carried. The said frame-work 2 is further provided at each end of the truck or carrier with other outwardly and upwardly 30 extending arms 9, and mounted in the free end-portions of said arms are guide-rods 10 which extend laterally across the ends of the said truck or carrier. The fabric 5 may be carried from the said guide-rod 8 over either 35 one or the other of said guide-rods 10. In like manner, the frame-work 2 is provided with centrally disposed lugs 11 in the free end-portions of which is mounted, so as to extend laterally across the said truck or carrier and beneath the said platform 4, another guide-rod 12 over which the fabric 5 is carried after passing over one of the said 40 guide-rods 10, substantially in the manner shown in the several figures of the drawings.

Secured to each side of the frame-work 2 and upon the inner-surfaces thereof, by means of studs 13 at the top and bottom of the frame-work, are a pair of guide-bars 14. The 45 said pair of guide-bars 14 upon the one side 65 of said truck or carrier are provided with

teeth or serrations 15 upon one of their edges, substantially as shown and for the purposes to be hereinafter disclosed.

Slidably arranged upon one pair of oppositely placed guide-bars 14 are a pair of spreader-brackets 16, to the lower portions of which is secured, in any suitable manner, a spreader-blade 17 which extends laterally across the interior of the truck or carrier. The said spreader-blade is provided at one 75 edge with an upwardly curved portion 18. Secured upon the bottom of each of said spreader-brackets 16, in any suitable manner, is a shoe 19 which is provided at its one end with a curved portion 20 corresponding 80 with the said curved portion 18 of said spreader-blade 17.

A shaft 21 is mounted in the said frame-work 2 in such a manner that it extends laterally across the interior of the truck or carrier, and is capable of an oscillatory movement between the sides of the said frame-work. Secured to this shaft 21, by means of set-screws 22, or in any other suitable manner, are a pair of levers or arms 23, and operatively secured to the free end-portion of each lever or arm 23 is a suitable roller 24, the said rollers 24 being arranged in and being adapted to move back and forth in a channel or groove of suitable guide-members 25 or elements 25 connected with each spreader-bracket 16, said shaft 21, the said levers or arms 23 and the said rollers 24, in connection with the said spreader-brackets 16, assure an even and smooth operation of the said spreader-blade 17 when the same is caused to slide up and down upon the said guide-bars 14, during the operation of the clamping mechanism, as will be presently described. In like manner, slidably arranged upon the other pair of oppositely placed guide-bars 14, are a pair of spreader-brackets 26, to the lower portions of which are secured, in any suitable manner, a spreader-blade 27 which extends laterally across the interior of the truck or carrier. This said spreader-blade 27 is provided at one edge with an upwardly curved portion 28. Secured upon the bottom of each spreader-bracket 26, in any suitable manner, is a shoe 29 which is provided at one 105 end with a curved portion 30 corresponding with the said curved portion 28 of said spreader-blade 27.

A shaft 31 is mounted in the frame-work 2, in such a manner, that it extends laterally 120 across the interior of the truck or carrier, and is capable of an oscillatory movement between the sides of the said frame-work. Secured to this shaft 31, by means of set-screws 32, or in any other suitable manner, are a pair of levers or arms 33, and operatively secured to the free end-portion of each lever or arm 33 is a suitable roller 34, said rollers 34 being arranged and being adapted to move back and forth in a suitable channel or 130

groove of a suitable guide-member or element 35 connected with each spreader-bracket 26. The said shaft 31, the said levers or arms 33, and the said rollers 34 in connection with the said spreader-brackets 26, assure an even and smooth operation of said spreader-blade 27, when the same is caused to slide up and down upon the said guide-bars 14, during the operation of the clamping mechanism, as will be presently described.

Rigidly secured in the frame-work 2, at each end thereof and extending laterally across the truck or carrier, beneath the platform 4, is a rod 36, and suitably fixed in proper position upon each rod 36, by means of a set-screw 37, or any other suitable fastening means, is a suitable trip-device or actuating dog 38, substantially as shown and for the purposes to be presently more fully described.

The clamping devices located at each end of the cutting table or bench 1 are exactly alike, and each device comprises a main-plate, body or member 39 which extends laterally across the said cutting-table, and the same is provided at its inner longitudinal edge with an upwardly extending flange 40.

Adjustably secured at each end of the said main body or member 39 is a suitably formed block or plate 41 which is provided at its outer end with a downwardly extending lug 42 adapted to engage with the side-edges of said cutting-table or bench 1, to hold the clamping device in a proper position against lateral displacement when the said blocks or plates have been rigidly fixed in place by means of suitably shaped straps or yoke-pieces 43 which are recessed and extend over the tops of said blocks or plates 41, and are firmly held down secured upon the same, in a binding manner, by means of bolts 44 which extend through the ends of said straps 43 and are screwed into the said main body or member 39, as will be clearly evident.

Secured to the flange or upwardly extending member 40 of said main body 39 are a pair of forwardly extending frame-like members or brackets 45, one adjacent to each end of said main body or member 39. Each of the said frame-like members 45 are provided with a backwardly extending arm 46 and laterally mounted between said members or brackets 45 is a shaft 47. Secured rigidly to said shaft 47 and adjacent to each member 45 are suitable cams 48. Rigidly connected to the free ends or portions of a shaft 49, rotatably mounted in the free ends of said backwardly extending arms 46 of the said frame-like members 45, are clamp-iron carriers 50. These carriers are provided with suitably formed rollers 51, suitably mounted upon studs 52 which are rigidly secured to said clamp-iron carriers 50. These said rollers 51 are adapted to engage with the

cams 48 for the purpose of raising said clamp-iron carriers 50 and lowering the same during the operation of the clamping devices. The said clamp-iron carriers 50 are each provided with forwardly extending arms 53, 70 and pivotally secured between the free ends of said arms 53, is a clamp-iron or weight 54. Pivotally secured to each of said forwardly extending arms 53, upon the inner side thereof, and extending preferably in alinement 75 therewith, are a pair of arms 55, said arms being capable of oscillatory movement. Secured, in a suitable manner, to the free ends of said arms 55 is a pin-clamp in the form of cross-bar 56 which extends laterally 80 in back of said clamp-iron or weight 54, and is provided with downwardly extending or retaining pins 57, which are pointed or sharpened at their free ends. The said cross-bar 56 is held in its normal position, 85 back of said clamp-iron or weight 54, so as to rise with the same when the clamping-device is operated, for the insertion or arrangement of a layer of fabric thereunder. This is accomplished by means of a trip-bar 90 58, the free end 59 of which projects beneath the said cross-bar 56 and supports the same. This said trip-bar 58 extends backwardly along the inner side of one of the said forwardly extending arms 53 and is slidably 95 supported by means of a bracket-piece 60 which is provided with a pair of pins 61 between which the said trip-bar 58 passes. The said trip-bar 58 is furthermore bent outwardly, as at 62, so that it passes beneath 100 one of the said clamp-iron carriers 50, and the end 64 thereof is formed with a slot or elongated opening 65, so as to be slidably secured to the outer side of a lug 63 forming an integral part of said clamp-iron carrier 50, 105 by means of a suitably arranged screw or similar element 66 which projects into said slot or elongated opening 65. The end-portion 64 of said trip-bar 58 is also provided with an outwardly extending lug or projection 67. For the purpose of keeping the said trip-bar 58 normally in its supporting position with relation to said cross-bar 56, there is provided a coiled spring 68, one end of which is secured to a hook 69, or similar 115 fastening means, upon the under side of said trip-bar 58, and the other end of which is secured in any suitable manner to the side of said forwardly extending arm 53. Trip-pieces 70 are secured in any well-known 120 manner to the frame work 2 of the truck or carrier in suitable location so that at the proper time they will engage with the lug or projections 67 to force the same back and then operate the trip-bar 58 to release the 125 cross-bar 56 so that the same may be dropped and its pins 57 engage with the fabric.

Secured by means of rivets 71, or any other suitable means, to the frame-members 130

45, are forwardly extending arms 72, upon the free end-portions of which is secured, in any suitable manner, a bed-plate 73 which extends laterally beneath the said clamp-
5 iron or weight 54 and said cross-bar 56. The purpose of said bed-plate 73 is to provide a rigid and level base over which the ends of the folds of fabric 5 are laid, so as to be firmly held or secured by said clamp-iron 54.
10 Rotatably arranged upon studs 74, upon the outer sides of the free end of each of said forwardly extending arms 53 of said clamp iron carriers 50, are rollers 75, and arranged upon the shaft 47 is a friction-clutch 76
15 which is provided with an upwardly extending arm 77. The said friction-clutch 76 may be of any ordinary and well-known type, of which there are numerous mechanical constructions obtainable. The said friction-clutch of itself forms an element in the combination of devices comprising the clamp-mechanism of the present invention. The said friction-clutch 76 clutches or grips the shaft 47 when revolved in one direction and releases its clutch or grip upon said shaft 47 and revolves loosely thereon, when the same is revolved in the opposite direction. The purpose which the said friction-clutch 76 accomplishes is to drive or revolve said shaft
20 47 in one direction only, thereby rotating the cams 48, so that they will impart a lifting movement to the clamp-iron carriers 50, when the upwardly extending arm 77, which is rigidly secured to said friction-clutch 76,
25 is pushed backward by the operative contact therewith of the trip-device or actuating dog 38. After the fabric 5 has been deposited under the clamp-iron 54, and the carriage or truck is moved in the opposite direction, the said clamp-iron 54 drops upon the fabric 5 of its own weight, entailing in this downward movement the lowering of the clamp-iron carriers 50 with their rollers 51, which in turn act upon said cams 48
30 causing an opposite revolution of the same until the said clamp-iron 54 comes to rest in its clamping position upon the piled up fabric 5. The friction-clutch 76 is returned to its normal and initial position, ready for
35 the next contact of the trip-device or actuating-dog 38, and in position to again revolve said shaft 47 in its operative direction to lift said clamp-iron 54, by being revolved in the opposite direction upon said shaft 47,
40 which it does not grip during said reversed revolution. This return revolution of said friction-clutch 76 is caused by the action of a coiled spring 76', one end of which is secured to the lower end of said upwardly extending arm 77, and the opposite end of which is secured, in any suitable manner, to the flange 40 of said body or member 39. The clutch 76 is used simply to provide a suitable means for regulating the position of the cams 48
45 with relation to the clamp-iron carriers 50,

as the clamping level of the said clamp-iron or weight 54 is necessarily raised, as the increasing layers of fabric 5 are deposited thereunder.

The means for accommodating the respective spreader-blades 17 and 27 comprises the following mechanism. Each of the previously mentioned spreader-brackets 16 and 26 are provided with studs 78 which are arranged or connected with said spreader-brackets in such a manner that they are capable of oscillatory movements. Slidably arranged in the free ends of these studs 78 is a dog rod 79 which is provided at or near one end with a shoulder or flange 80, and in like manner, is provided at or near its other end with a shoulder or flange 81. The end of said dog rod 79 provided with the shoulder or flange 80 is made with a nose-piece 82, adapted to engage with one of the teeth or serrations 15 upon the previously mentioned guide-bar 14. A coiled spring 83 one end of which is secured to a lug 84 integrally formed upon said spreader-brackets, and the other end of which is secured by means of a screw-eye or other fastening means 85 to the upper end-portion of said rod 79, tends to keep said nose-piece normally in engagement with the teeth or serrations 15 of the guide-bars 14. The operation and purpose of the above described device is as follows; it is desirable to maintain the said spreader-blades always slightly above the layers of fabric 5, which they are spreading, so as to reduce friction in their operation and produce a more smoothly 95 and evenly spread layer of fabric, and to accomplish this result, it is necessary to constantly raise the spreading level or operating level of the said spreader-blades as the layers of fabric piles up underneath the same. This is produced in the following manner:—The nose-piece 82 engages with one of the teeth or serrations 15 of said guide-bars 14, and when the spreader-brackets slide downwardly on said guide-bars 14, the shoulder or flange 80 is brought in engagement with the said studs 78 and thus limits the downward movement of the said spreader-brackets, stopping the same so that the spreader-blades carried by said spreader-brackets are presented in a position slightly above the layers of fabric 5, and in position to spread or lay the fabric. When the spreader-brackets are raised by the action of the clamping device, which will be subsequently described, the rod 79 slides 110 through the stud 78. The height of the upward swing of the clamping-device is governed by the amount of fabric beneath the clamping iron or weight, the upward movement of the clamping device carrying the spreader-bracket upwardly until the stud 78 is brought in contact with the shoulder or flange 81 upon the upper end of said rod 79. The said rod 79 is then carried upwardly until the nose-piece 82 upon its lower end is 115 120 125 130

caused to slide over the teeth or serrations 15 of the guide-bars 14, until the said nose-piece 82 engages with the next tooth or serration above; then, when the said spreader bracket 5 is again dropped it will be brought to a stop at a point as much higher above the layers of fabric, as the distance between the teeth or serrations 15, as will be clearly evident, and as will be understood more particularly from 10 an inspection of Figs. 4 and 5 of the drawings.

As it is convenient to keep a record of the number of layers spread by the machine a counting mechanism 86 of any well known 15 type may be provided. This mechanism is operated by means of a spring-connection 87 which is attached at one end with the operating arm 88 of said counting-mechanism, and at the other end with a lug or projection 89 20 secured to said stud 78, so as to move with each oscillation of the stud in a manner clearly to be understood from the accompanying drawings.

Having thus described the general construction and essential features of a machine or apparatus embodying the principles of this invention, it now remains to describe the operations thereof while performing the work of stretching or spreading the cloth or fabric 30 5 upon the cutting table 1.

Referring now, more particularly to Figs. 3 of the drawings, there is illustrated therein, the truck or carrier as it is approaching and beginning to operate the clamping device, 35 after having spread a fold of the fabric 5 upon the cutting-table or bench 1.

While the truck or carrier is moving along the cutting-table, both spreader-blades 17 and 27 are down; but, as illustrated in Fig. 3, 40 the spreader-blade 17 is guiding or spreading the fabric, while the spreader-blade 27 is idle. When the truck or carrier reaches the clamping device, the idle spreader-blade 27 is caused to pass over the top of the forwardly 45 extending arms 53 of the clamp-iron carrier 50, the shoes 29 of the spreader-brackets 26 riding over the rollers 75. By this time the truck or carrier reaches such a position that, the clamp-operating device 38 is brought in 50 contact with the arm 77 of the friction clutch 76, thereby driving the same backwardly and thus actuating the shaft 47 and cams 48. The latter engage the rollers 51 on the said clamp-iron carriers 50 with a lifting 55 motion, which being imparted to the forwardly extending arms 53 of said clamp-iron carriers 50, imparts the upward movement 60 to the clamp-iron or weight 54, thereby lifting the same and allowing the still forwardly 65 moving spreader-blade 17 to pass beneath the same, and to carry the fabric 5 therewith, as is shown more particularly in Fig. 4 of the accompanying drawings. By the time the fabric 5 has been inserted beneath the clamp- 70 ing-iron or weight 54, and above the bed-

plate 73, the trip-piece 70 upon the truck or carrier reaches and pushes back the lug or projection 67 of the trip-bar 58 thereby releasing or drawing away the supporting end 59 from its supporting contact with the said 70 cross-bar 56 and allowing the same to drop, so that the pins 57 will engage the fabric 5 and hold the same, while the truck or carrier is then removed in the opposite direction, so as to withdraw the said spreader-blade 17. 75 While the truck or carrier is being moved in the opposite direction, away from the clamping-device, the operation of the clutch 76 cams 48, and other parts, are reversed, and the clamp-iron or weight 54 is thus al- 80 lowed to drop upon the end of the fabric 5, just deposited thereunder, whereby the same is firmly held, while the spreader-blade 27 is lowered by the descending arms 53 of the said 85 clamp-iron carriers 50 to its spreading level and engages with that portion of the fabric 5 to be spread, to form the next layer. The truck or carrier is then pushed on toward the clamping-device at the other end of the cutting table 1, which is operated in the same 90 manner, and, under the clamp-iron or weight of which the said spreader-blade 27 de- 95 posits the next layer of fabric, and thus the truck or carrier is shifted back and forth between the two clamping devices, depositing layer upon layer of fabric upon the cutting-table or bench, as will be clearly evident.

As the truck or carrier moves away from the clamping device, the clamp-iron carrier 50, and its forwardly extending arms 53, 100 drop downwardly and carry with them the said trip-bar 58. The end 59 of said bar, which is chamfered, snaps over the cross-bar 56 and the tension of the spring 68 returns said trip-bar 58 and its end 59 to its support- 105 ing relation with said cross-bar 56, so that the same may be raised, when the clamping device is again operated, in order that the fabric 5 may be deposited thereunder.

I am aware that changes may be made in 110 the various arrangements and combinations of parts, as well as in the details of the construction of the same without departing from the scope of the present invention, as defined in the appended claims. Hence, I do not 115 limit my invention to the exact arrangements and combinations of the devices and parts, as illustrated in the accompanying drawings, and as described in the accompanying specification, nor do I confine myself to the exact 120 details of the construction of the said parts.

I claim:—

1. In an apparatus for spreading fabric upon a cutting table, the combination with a cutting table, of a bolt-carrying truck 125 movable back and forth upon said table, means carried by said truck for spreading the fabric in layers upon said table, a clamp- ing device at each end of the table, comprising a pair of brackets, a pair of laterally ex- 130

tending shafts mounted between said brackets, oscillatory clamp-iron carriers mounted upon one of said shafts, a clamp-iron carried by said clamp-iron carriers for clamping the 5 fabric, cams mounted upon the other shaft adapted to be brought into engagement with the clamp-iron carriers for oscillating the same, and means upon the truck for actuating said cam-carrying shaft, substantially as 10 and for the purposes set forth.

2. In an apparatus for spreading fabric upon a cutting table, the combination with a cutting table, of a bolt-carrying truck movable back and forth upon said table, 15 means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft 20 adapted to be brought into engagement with the clamp-iron carriers for oscillating the same, and means upon the truck for actuating said cam-carrying shaft, and a pin-clamp provided with a series of downwardly extending holding pins mounted between said 25 clamp-iron carriers, substantially as and for the purposes set forth.

3. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft 40 adapted to be brought into engagement with the clamp-iron carriers for oscillating the same, and means upon the truck for actuating said cam-carrying shaft, and means for securing each clamping device in position 45 against lateral displacement consisting of a flanged plate to which said brackets are secured, blocks arranged upon said plate, each block being provided with a downwardly extending lug adapted to engage the side-edge 50 of the cutting table, a strap arranged over each block, and bolts connected with said strap and secured to said flanged plate, substantially as and for the purposes set forth.

4. In an apparatus for spreading fabric 60 upon a cutting table, the combination with a cutting table, of a bolt-carrying truck movable back and forth upon said table, means carried by said truck for spreading the fabric in layers upon said table, a clamp- 65 ing device at each end of the table, comprising

ing a pair of brackets, a pair of laterally extending shafts mounted between said brackets, oscillatory clamp-iron carriers mounted upon one of said shafts, a clamp-iron carried by said clamp-iron carriers for clamping the 70 fabric, cams mounted upon the other shaft adapted to be brought into engagement with the clamp-iron carriers for oscillating the same, and means upon the truck for actuating said cam-carrying shaft, and a pin-clamp 75 provided with a series of downwardly extending holding pins mounted between said clamp-iron carriers, and means for securing each clamping device in position against lateral displacement consisting of a flanged plate to which said brackets are secured, 80 blocks arranged upon said plate, each block being provided with a downwardly extending lug adapted to engage the side-edge of the cutting table, a strap arranged over each 85 block, and bolts connected with said strap and secured to said flanged plate, substantially as and for the purposes set forth.

5. In an apparatus for spreading fabric upon a cutting table, the combination with a cutting table, of a bolt-carrying truck movable back and forth upon said table, means carried by said truck for spreading the fabric in layers upon said table, and a clamping device at each end of the table, comprising a 90 pair of brackets, a laterally extending shaft mounted between said brackets, oscillatory clamp-iron carriers mounted upon said shaft, a clamp-iron carried by said clamp-iron carriers for clamping the folded end-portions of 100 the spread fabric, a pin-clamp provided with a series of downwardly extending holding pins, means for actuating said clamp-iron carrier, and a slidably arranged trip-bar normally in supporting engagement with said 105 pin-clamps, but adapted to be withdrawn from said supporting engagement when said clamp-iron is in its raised position, and returned to said supporting engagement when the clamp-iron has been lowered upon the 110 fabric, substantially as and for the purposes set forth.

6. In an apparatus for spreading fabric upon a cutting table, the combination with a cutting table, of a bolt-carrying truck movable back and forth upon said table, means carried by said truck for spreading the fabric in layers upon said table, and a clamping device at each end of the table, comprising a pair of brackets, a laterally extending shaft 115 mounted between said brackets, oscillatory clamp-iron carriers mounted upon said shaft, a clamp-iron carried by said clamp-iron carriers for clamping the folded end-portions of the spread fabric, a pin-clamp provided with a series of downwardly extending holding pins, means for actuating said clamp-iron carrier, and a slidably arranged trip-bar normally in supporting engagement with said 120 pin-clamp, but adapted to be withdrawn 125 from said supporting engagement when said clamp-iron is in its raised position, and returned to said supporting engagement when the clamp-iron has been lowered upon the 130 fabric, substantially as and for the purposes set forth.

from said supporting engagement when said clamp-iron is in its raised position, and returned to said supporting engagement when the clamp-iron has been lowered upon the fabric, and means for securing each clamping device in position against lateral displacement consisting of a flange plate to which said brackets are secured, blocks arranged upon said plate, each block being provided with a downwardly extending lug adapted to engage the side-edge of the cutting table, a strap arranged over each block, and bolts connected with said strap and secured to said flanged plate, substantially as and for the purposes set forth.

7. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, and means upon the truck for actuating said cam-carrying shaft, a pin-clamp provided with a series of downwardly extending holding pins pivotally mounted between said clamp-iron carriers, and a slidably arranged trip-bar normally in supporting engagement with said pin-clamp, but adapted to be withdrawn from said supporting engagement when said clamp-iron is in its raised position, and returned to said supporting engagement when the clamp-iron has been lowered upon the fabric, substantially as and for the purposes set forth.

8. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, and means upon the truck for actuating said cam-carrying shaft, a pin-clamp provided with a series of downwardly extending holding pins pivotally mounted between said clamp-iron carriers, and a slidably arranged trip-bar normally in supporting engagement with said pin-clamp, but adapted to be with-

drawn from said supporting engagement when said clamp-iron is in its raised position and returned to said supporting engagement when the clamp-iron has been lowered upon the fabric, and means for securing each clamping device in position against lateral displacement consisting of a flanged plate to which said brackets are secured, blocks arranged upon said plate, each block being provided with a downwardly extending lug adapted to engage the side-edge of the cutting table, a strap arranged over each block, and bolts connected with said strap and secured to said flanged plate, substantially as and for the purposes set forth.

9. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, a friction clutch upon said cam-carrying shaft, an arm extending from said clutch, and means carried by said truck adapted to be brought into engagement with said arm for actuating said clutch, substantially as and for the purposes set forth.

10. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, a friction clutch upon said cam-carrying shaft, an arm extending from said clutch, and means carried by said truck adapted to be brought into engagement with said arm for actuating said clutch, and a pin-clamp provided with a series of downwardly extending holding pins mounted between said clamp-iron carriers, substantially as and for the purposes set forth.

11. In an apparatus for spreading fabric upon a cutting table, the combination with a cutting table, of a bolt-carrying truck movable back and forth upon said table, means carried by said truck for spreading the fabric

in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, a friction clutch upon said cam-carrying shaft, an arm extending from said clutch, and means carried by said truck adapted to be brought into engagement with said arm for actuating said clutch, and means for securing each clamping device in position against lateral displacement consisting of a flanged plate to which said brackets are secured, blocks arranged upon said plate, each block being provided with a downwardly extending lug adapted to engage the side-edge of the cutting table, a strap arranged over each block, and bolts connected with said strap and secured to said flanged plate, substantially as and for the purposes set forth.

12. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, a friction clutch upon said cam-carrying shaft, an arm extending from said clutch, and means carried by said truck adapted to be brought into engagement with said arm for actuating said clutch, and a pin-clamp provided with a series of downwardly extending holding pins mounted between said clamp-iron carriers, and means for securing each clamping device in position against lateral displacement consisting of a flanged plate to which said brackets are secured, blocks arranged upon said plate, each block being provided with a downwardly extending lug adapted to engage the side-edge of the cutting-table, a strap arranged over each block, and bolts connected with said strap and secured to said flanged plate, substantially as and for the purposes set forth.

13. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of

brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, a friction clutch upon said cam-carrying shaft, an arm extending from said clutch, and means carried by said truck adapted to be brought into engagement with said arm for actuating said clutch, a pin-clamp provided with a series of downwardly extending holding pins pivotally mounted between said clamp-iron carriers, and a slidably arranged trip-bar normally in supporting engagement with said pin-clamp, but adapted to be withdrawn from said supporting engagement when said clamp-iron is in its raised position, and returned to said supporting engagement when the clamp-iron has been lowered upon the fabric, substantially as and for the purposes set forth.

14. In an apparatus for spreading fabric upon a cutting table, the combination with a cutting table, of a bolt-carrying truck movable back and forth upon said table, means carried by said truck for spreading the fabric in layers upon said table, a clamping device at each end of the table, comprising a pair of brackets, a pair of laterally extending shafts mounted between said brackets, oscillatory clamp-iron carriers mounted upon one of said shafts, a clamp-iron carried by said clamp-iron carriers for clamping the fabric, cams mounted upon the other shaft adapted to be brought into engagement with the clamp-iron carriers for oscillating the same, a friction clutch upon said cam-carrying shaft, an arm extending from said clutch, and means carried by said truck adapted to be brought into engagement with said arm for actuating said clutch, a pin-clamp provided with a series of downwardly extending holding pins pivotally mounted between said clamp-iron carriers, and a slidably arranged trip-bar normally in supporting engagement with said pin-clamp, but adapted to be withdrawn from said supporting engagement when said clamp-iron is in its raised position, and returned to said supporting engagement when the clamp-iron has been lowered upon the fabric, and means for securing each clamping device in position against lateral displacement consisting of a flanged plate to which said brackets are secured, blocks arranged upon said plate, each block being provided with a downwardly extending lug adapted to engage the side-edge of the cutting table, a strap arranged over each block, and bolts connected with said strap and secured to said flanged plate, substantially as and for the purposes set forth.

15. In an apparatus for spreading fabric

upon a cutting table, the combination with a cutting table, of a bolt-carrying truck movable back and forth upon said table, vertical guide-bars, spreader-brackets, said brackets being arranged in pairs, a spreader-blade between said brackets, each bracket being provided with a channeled portion, a laterally extending shaft mounted in said truck, and arms extending from said shaft, each arm 10 being provided at its free end with a roller arranged within a channeled portion of a spreader-bracket, substantially as and for the purposes set forth.

16. In an apparatus for spreading fabric upon a cutting table, the combination with a cutting table, of a bolt-carrying truck movable back and forth upon said table, vertical guide-bars, spreader-brackets, said brackets being arranged in pairs, a spreader-blade between said brackets, each bracket being provided with a channeled portion, a laterally extending shaft mounted in said truck, and arms extending from said shaft, each arm being provided at its free end with a roller arranged within a channeled portion of a spreader-bracket, and a clamping device at each end of the table for clamping the folded end-portions of the spread fabric, substantially as and for the purposes set forth.

30 17. In an apparatus for spreading fabric upon a cutting table, the combination with a cutting table, of a bolt-carrying truck movable back and forth upon said table, vertical guide-bars, a spreader-bracket slidably arranged upon each guide bar, means connected with a bracket and engaging with a guide bar for regulating the sliding movement of the bracket, and a spreader-blade between each pair of brackets, each bracket being provided with a channeled portion, a laterally extending shaft mounted in said truck, and arms extending from said shaft, each arm being provided at its free end with a roller arranged within a channeled portion of a spreader-bracket, substantially as and for the purposes set forth.

18. In an apparatus for spreading fabric upon a cutting table, the combination with a cutting table, of a bolt-carrying truck movable back and forth upon said table, vertical guide-bars, a spreader-bracket slidably arranged upon each guide bar, means connected with a bracket and engaging with a guide bar for regulating the sliding movement of the bracket, and a spreader-blade between each pair of brackets, each bracket being provided with a channeled portion, a laterally extending shaft mounted in said truck, and arms extending from said shaft, each arm being provided at its free end with a roller arranged within a channeled portion of a spreader-bracket, and a clamping device at each end of the table for clamping the folded end-portions of the spread fabric, substantially as and for the purposes set forth.

19. In an apparatus for spreading fabric upon a cutting table, the combination with a cutting table, of a bolt-carrying truck movable back and forth upon said table, vertical guide-bars, one of said guide-bars being provided with serrations, a spreader-bracket slidably arranged upon each guide bar, a spreader-blade between each pair of brackets, and means connected with a bracket for regulating the sliding movement of the bracket, consisting of an oscillatory stud, a spring-controlled rod slidably connected with said stud, said rod having one end thereof in slidable engagement with the serrations of a guide-bar, and said rod being provided with a flange forming a stop, substantially as and for the purposes set forth.

20. In an apparatus for spreading fabric upon a cutting table, the combination with a cutting table, of a bolt-carrying truck movable back and forth upon said table, vertical guide-bars, one of said guide-bars being provided with serrations, a spreader-bracket slidably arranged upon each guide bar, a spreader-blade between each pair of brackets, and means connected with a bracket for regulating the sliding movement of the bracket, consisting of an oscillatory stud, a spring-controlled rod slidably connected with said stud, said rod having one end thereof in slidable engagement with the serrations of a guide-bar, and said rod being provided with a flange forming a stop, each bracket being provided with a channeled portion, a laterally extending shaft mounted in said truck, and arms extending from said shaft, each arm being provided at its free end with a roller arranged within a channeled portion of a spreader-bracket, substantially as and for the purposes set forth.

21. In an apparatus for spreading fabric upon a cutting table, the combination with a cutting table, of a bolt-carrying truck movable back and forth upon said table, vertical guide-bars, one of said guide-bars being provided with serrations, a spreader-bracket slidably arranged upon each guide bar, a spreader-blade between each pair of brackets, and means connected with a bracket for regulating the sliding movement of the bracket, consisting of an oscillatory stud, a spring-controlled rod slidably connected with said stud, said rod having one end thereof in slidable engagement with the serrations of a guide-bar, and said rod being provided with a flange forming a stop, each bracket being provided with a channeled portion, a laterally extending shaft mounted in said truck, and arms extending from said shaft, each arm being provided at its free end with a roller arranged within a channeled portion of a spreader-bracket, and a clamping device at each end of the table for clamping the folded end-portions of the spread fabric, substantially as and for the purposes set forth.

22. In an apparatus for spreading fabric upon a cutting table, the combination with a cutting table, of a bolt-carrying truck movable back and forth upon said table, a clamping device comprising a pair of brackets, a laterally extending shaft mounted between said brackets, oscillatory clamp-iron carriers mounted upon said shaft, a clamp-iron carried by said clamp-iron carriers, vertical 10 guide - bars connected with said truck, spreader-brackets slidably arranged upon said guide bars, and a connecting spreader-blade between said spreader brackets, said blade being adapted to be brought to rest 15 upon said clamp-iron carriers so as to be moved in an upward direction by said carriers, substantially as and for the purposes set forth.

23. In an apparatus for spreading fabric upon a cutting table, the combination with a cutting table, of a bolt-carrying truck movable back and forth upon said table, a clamping device comprising a pair of brackets, a laterally extending shaft mounted between 25 said brackets, oscillatory clamp-iron carriers mounted upon said shaft, a clamp-iron carried by said clamp-iron carriers, vertical guide - bars connected with said truck, spreader-brackets slidably arranged upon 30 said guide bars, and a connecting spreader-blade between said spreader brackets, said blade being adapted to be brought to rest upon said clamp-iron carriers so as to be moved in an upward direction by said carriers, and means connected with a spreader bracket and engaging with a guide bar for regulating the sliding movement of the 35 spreader brackets, each bracket being provided with a channeled portion, a laterally extending shaft mounted in said truck, and arms extending from said shaft, each arm being provided at its free end with a roller arranged within a channeled portion of a spreader-bracket, substantially as and for the purposes set forth.

spreader brackets, substantially as and for the purposes set forth.

24. In an apparatus for spreading fabric upon a cutting table, the combination with a cutting table, of a bolt-carrying truck movable back and forth upon said table, a clamping device comprising a pair of brackets, a laterally extending shaft mounted between 45 said brackets, oscillatory clamp-iron carriers mounted upon said shaft, a clamp-iron carried by said clamp-iron carriers, vertical guide - bars connected with said truck, spreader-brackets slidably arranged upon 50 said guide bars, and a connecting spreader-blade between said spreader brackets, said blade being adapted to be brought to rest upon said clamp-iron carriers so as to be moved in an upward direction by said carriers, and means connected with a spreader bracket and engaging with a guide bar for regulating the sliding movement of the 55 spreader brackets, each bracket being provided with a channeled portion, a laterally extending shaft mounted in said truck, and arms extending from said shaft, each arm being provided at its free end with a roller arranged within a channeled portion of a spreader-bracket, substantially as and for 60 the purposes set forth.

In testimony, that I claim the invention set forth above I have hereunto set my hand this first day of September, 1908.

AARON RATNER.
